UNITED STATES PATENT OFFICE.

ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

NON-RENEWABLE FUSE.

1,114,340.

Specification of Letters Patent.

Patented Oct. 20, 1914.

Application filed March 17, 1913. Serial No. 754,922.

To all whom it may concern:

Be it known that I, ROBERT C. COLE, a citizen of the United States, residing at Hartford, in the county of Hartford and State of Connecticut, have invented a new and useful Improvement in Non-Renewable Fuses, of which the following is a specification.

This invention relates to the construction of inclosed electric safety fuses having single and multiple fusible links of the ferrule, lug and knife blade terminal types.

Electric fuses are essentially intended to be safety devices. They are designed to be placed in circuits and to open on an abnormal rise of current and thus protect apparatus connected with the circuits and objects adjacent to the circuits and the fuses. If they do not blow when the conditions become dangerous they are not safety devices. Much thought and study has been given and much labor and expense has been incurred in order to devise fuses that will blow accurately under the predetermined conditions and thus be dependable safety means. It is required that the fusible elements be inclosed in order to eliminate the dangers of the opening of the circuits when the fusible elements melt. Fusible elements that are inclosed cannot be seen. To save expense unscrupulous persons and those not skilled in the art frequently after a fuse has blown, insert a new fusible element in place of the one that has been destroyed. As a result it often happens that fusible elements of a capacity not warranted by the conditions have been placed in fuses and because the elements could not be seen these have been passed as safety devices, on the assumption that the elements were of the proper capacity and of the rating stated on the fuses, whereas, as a matter of fact the fusible elements were of so much greater capacity that the fuses instead of being safety devices were an element of danger.

The object of this invention is to so construct an inclosed fuse that after the fusible element originally placed therein has been disrupted or destroyed, the structure cannot be disassembled or manipulated in such a manner that another fusible element can be placed in the interior. To attain this object the fuses are so manufactured that the terminals after once assembled cannot be removed without destroying or causing visual

damage to the structure, or cannot be drilled or cut and a fusible element passed through the inside and connected with the terminal so as to complete the circuit through the interior. The only way that a fuse which embodies this invention can be made use of after it has been blown is by connecting the terminals by a link which passes over the exterior, a condition which instantly shows that the fuse is not in its original state.

Figure 1 of the accompanying drawings is a side view with part cut in central section of a single link inclosed fuse of the ferrule terminal type which embodies the invention. Fig. 2 shows a similar view of a fuse of the same type which is constructed according to this invention and is vented in such manner as to permit the escape of gases developed by the blowing of the fuse, the vent openings being arranged in such manner that it is practically impossible to pass a fuse wire through them from one terminal to the other. Fig. 3 is a side view with part cut in central section of a multiple link inclosed fuse of the knife blade terminal type. Fig. 4 shows a transverse section taken on the plane indicated by the dotted line 4-4 on Fig. 3, looking in the direction indicated by the arrows. Fig. 5 is a side view with a part cut in central section of a multiple link inclosed fuse of the knife blade terminal type having a different construction from that shown in Fig. 3. Fig. 6 shows a transverse section on the plane indicated by the dotted line 6-6 on Fig. 5, looking in the direction indicated by the arrows.

The fuses shown have non-conducting casings 1 which are desirably made of tubular pieces of vulcanized fiber. In the form first shown metallic end caps 2 are forced on the ends of the casing. These end caps may be made of brass or steel, as desired, and their inner edges are crimped into the casing as at 3 so that after once being set they cannot be withdrawn. The closed ends of these caps are inset and connected therewith by solder 4, or any other desired means are the internal terminals 5 to which the ends of the fusible element 6 are secured. In the recessed ends of the caps are steel disks 7. These disks are case-hardened or made extremely hard in any other desired manner so that they cannot be punched, drilled or otherwise cut. It is desirable to locate brass disks 8 outside of the hard steel

disks and to hold these in place by spinning or otherwise turning the outer edges 9 of the caps over the edges of the disks. As a result of this construction, after a fusible element has become disrupted the end caps cannot be removed without destroying the casing and the steel disks cannot be perforated so as to permit a fusible element to be run through from one terminal to the other.

If it is desired to provide vents for the escape of gases when the fuse blows, openings 10 may be made through the end walls of the caps. In this case instead of using a flat hardened steel disk, as shown in Fig. 1, the hardened steel disk may be cupped as is the disk 11 shown in Fig. 2. Vent openings 12 may be made through the sides of this cup. The cupped disk is secured by turning over the outer end of the cap. This disk is hardened so that it cannot be perforated and the vent openings are in such position that it is impossible to push a wire through them and through the casing and out through the vent openings at the other end and thus electrically connect the terminals together in the interior.

In the form shown in Figs. 3 and 4 the knife blade terminals 13 are connected with an anchoring spider 14 that fits within the casing. The internal terminals 5 of the fusible element 6 are connected with this spider which is attached to the external terminals. On the outside of the ends of the casing tight-fitting ferrules 15 are driven. These ferrules are desirably tapering and can be made of steel or brass, as desired, preferably the former. After these ferrules have been forced to place, pins 16 are driven through them and the casing and terminal anchors. These pins securely hold the terminals and the ferrules in place on the ends of the casing. Felt washers 17 may be placed over the ends of the casing and felt rings 18 may be placed around the ferrules. Over these are placed hardened steel caps 19, which after being located have their inner edges turned in over the edges of the ferrules that are held on by the pins. When the edges of the caps are thus turned in the parts cannot be removed for the caps cannot be drawn from the ferrules and the ferrules and terminal anchors cannot be removed because they are held by the concealed pins.

The front turned in edges of the hardened steel caps are preferably provided with openings 20. When a fusible element blows the gases can pass through the pores of the washers 17 and rings 18 and escape through these openings in the ends of the caps and thus relieve the pressure in the interior.

In the forms shown in Figs. 5 and 6, hardened steel ferrules 21 are driven on the ends of the casing and secured in place by the pins 16 which pass through the ferrules, the

casing and the arms of the terminal anchors. The front edge of this ferrule is turned up at 23 and on the ferrule is tightly set the end cap 24. The pins cannot be driven out as they are concealed so that the ferrules cannot be removed and the steel non-drillable caps are set so tightly on the ferrules that they cannot be removed without destroying or materially damaging the structure.

The invention claimed is:

1. An inclosed fuse having a fusible element, a casing inclosing said element and tool-resisting disks of the hardness of hardened steel permanently attached to and protecting the ends of the casing, whereby perforations cannot be easily cut from the exterior to the interior through said protecting disks to permit the insertion of a fusible element without substantial damage to the structure.

2. An inclosed fuse having a fusible element, a casing inclosing said element, and tool-resisting means of the hardness of hardened steel with vent openings permanently attached to and protecting the ends of the casing, whereby openings cannot be made from the exterior to the interior through said protecting means for the insertion of a fusible element without destroy- 95 ing the structure.

3. An inclosed fuse having a fusible element, a casing inclosing said element, and tool-resisting disks of the hardness of hardened steel permanently attached to the ends of the casing and protecting the ends of the fusible element whereby openings cannot be made from the exterior to the interior through said protecting disks for the insertion of a fusible element without destroy- 105 ing the structure.

4. An inclosed fuse having a fusible element, a casing inclosing said element, and hardened steel parts permanently attached to and protecting the ends of the casing so as to render it difficult to perforate the protected ends of the casing for the renewal of the fusible element.

5. An inclosed fuse having a fusible element, a casing inclosing said element, and means closing the ends of the casing, said means having hardened steel parts permanently attached to and obstructing the openings into the ends of the casing, whereby openings cannot be made into the ends of the casing for the insertion of a fusible element without destroying the structure.

6. An inclosed fuse having a fusible element, a casing inclosing said element, ferrules on the ends of said casing and hardened steel disks permanently attached to the ferrules and protecting the ends of said casing.

7. An inclosed fuse having a fusible element, a casing inclosing said element, and

hardened steel end caps permanently attached to the ends of said casing, whereby openings cannot be readily drilled through said end caps from the exterior into the 5 ends of the casing so as to permit the insertion of a conducting element without substantial and apparent mutilation of the structure.

8. An inclosed fuse having a fusible element, a casing inclosing said element and a tool-resisting disk of the hardness of hardened steel permanently attached to and protecting one end of the casing, whereby perforations cannot be easily cut from the exterior to the interior through said protecting disk to permit the insertion of a fusible element without substantial damage to the 10 15

structure, and means permanently closing the other end of the casing.

9. An inclosed fuse having a fusible element, a casing inclosing said element, and a hardened steel end cap permanently attached to one end of said casing, whereby openings cannot be readily drilled through said end cap from the exterior into the end 20 25 of the casing so as to permit the insertion of a conducting element without substantial and apparent mutilation of the structure, and means permanently closing the other end of the casing.
